MACHINE FOR SHRINKING HAT BATS

Homer A. Genest, Danbury, Conn., assignor to
United States Hat Machinery Corporation, New
York, N. Y., a corporation of Virginia

Application November 17, 1937, Serial No. 174,987

3 Claims. (Cl. 28—7)

This invention relates to the shrinking of felt articles—for example, bats from which fur or felt hats are made—and it has particular reference to the method and machine for effecting the starting operation on hat bats; this operation following the hardening of the bats in the usual manner.

The practice in starting is to roll up a number of bats in a piece of buriap or flannel, place them in a trough of a machine in such position that when the machine is in operation the tendency will be to wind the assembly tighter. After a machine has run a predetermined time, the roll of bats is removed, unrolled, turned over bottom side up, and again rolled from tip to brim, and the rewound assembly is placed in the machine and the operation repeated, after which the bats are rolled from one side to the other, placed back in the machine, and again manipulated. Next, the bats are turned over bottom side up and again rolled from side to side and manipulated in this condition. The four operations—that is, "two tips and two side rolls"—are called a "round". This operation has generally been carried on in machines provided with cages wherein the bat roll was supported in a trough between rolls or cages and the cages were provided with longitudinally extending rods forming a plurality of curved surfaces on the face thereof which acted upon the bats. In some instances, the surfaces of the drums were diagonally grooved so that a longitudinal spiral action took place. However, in all of them the action has been limited to the longitudinal extending operation.

An object of the present invention is to perform a double action—that is, the hat bats are acted upon both longitudinally and circumferentially.

A further object is a machine which simultaneously performs four operations upon the bats.

A still further object is a machine in which the trough for receiving the hat bats may be enlarged or reduced to receive hat bats of various sizes.

A still further object is a machine which is extremely flexible, economical, and in which the hat bats may be correctly and effectively started preliminary to the felting or shrinking operation.

Other objects will be in part obvious and in part pointed out more in detail hereinafter.

The invention accordingly consists in the features of construction, combination of elements, and arrangement of parts which will be exemplified in the construction hereafter set forth and the scope of the application of which will be indicated in the appended claims.

In the accompanying drawings, wherein like parts are indicated by like numerals:

Figure 1 is a plan view of the machine;

Fig. 2 is an end view of Fig. 1;

Fig. 3 is a more or less diagrammatic view showing the means for adjusting the hardening cages;

Fig. 4 is a fragmentary view taken on the line 4—4 of Fig. 1; and

Fig. 5 is an enlarged diagrammatic view showing the cages and the pressure rolls.

In general, the machine comprises a bottom supporting roll A, a top pressure roll B preferably having its axes in vertical alignment with the axis of roll A, and intermediate, horizontally arranged side rolls C and D which are spaced to either side of the center line between the axis of the rolls A and B. The top and bottom rolls A and B are circumferentially corrugated or grooved and the side walls C and D longitudinally corrugated or fluted. Means are also provided for spacing the top and bottom rolls and side rolls relative to one another to form a trough therebetween adapted to receive a roll of bats E to be manipulated in the machine.

More particularly, the machine includes a suitable frame 10 on which is journaled in suitable bearings 11 a longitudinally extending transverse shaft 12. The bottom roll A is secured in any suitable way on shaft 12 for rotation therewith. The surface of roll A is circumferentially corrugated to present a plurality of ridges 13 and grooves 14. Arranged above and spaced to either side of the vertical center of bottom roll A are corrugated side rolls or cages C and D, each roll comprising a pair of oppositely disposed heads 31 interconnected by spaced, transversely extending rods 32 preferably of circular cross section. Rolls C and D cooperate with roll A to support a roll of bats E between them; the side rolls C and D being adjustable horizontally to increase the width of the trough. In the machine shown, the rolls are respectively supported on shafts 17 and 18 adjacent the ends of the radially extending supporting arms 19 and 20, which arms are coaxially and pivotally supported on the shaft 12 adjacent the shaft bearings 11.

The arms 19 and 20 also extend below shaft 12 through an opening 23 in the top plate 24 of the frame 10 and terminate in adjusting fingers 21 and 22. The adjusting fingers engage a stop pin 25 fixed to a nut 26 which is adjustable along rod 27. Rod 27 is journaled in suitable bearings 28 in frame 10 and held therein by collars 29; the outer end being provided with a suitable adjusting wheel 30 to allow manual setting of arms 55

19 and 20. Rod 27 is oppositely threaded to either side of the vertical center through shaft 12, whereupon rotation of rod 27 the arms will adjust rolls C and D towards or away from one another, depending upon the direction of rotation.

Although rolls C and D could be mounted and adjusted horizontally in a number of ways, the particular arrangement shown conveniently enables the support of means for simultaneously rotating bottom roll A and side rolls D and C. The bottom roll A and cages 19 and 20 are interconnected for simultaneous rotation. This is accomplished through a gear 35 fixed on shaft 12, 15 which meshes with idlers 36 and 37 rotatably carried respectively by the radial arms 19 and 20 which, in turn, mesh with gears 38 and 39 fixed on shafts 17 and 18, respectively. With this arrangement, when gear 35 is rotated in a 20 counterclockwise direction to rotate bottom roll A in a counterclockwise direction, the motion will be transmitted to the cages through the idlers and gears to cause a similar rotation of rolls C and D. The shaft 12 may be rotated in any suitable way; in the embodiment shown there being provided a belt driven pulley 49 which is freely rotated on the end of shaft 12 and clutched into and out of engagement with shaft 12 as herein-after explained.

30 There is further provided a top pressure roll B preferably arranged with its axis in vertical alignment with the axis of roll A and is formed with a plurality of ridges 45 and grooves 46 in like manner thereto. In the machine shown, the 35 grooves of the two pressure rolls are in alignment, although, if desired, they could be staggered. The roll B is carried by a pivoted frame or carrier comprising a pair of arms 47 fixed to a rock shaft 48 journaled in brackets 49. The 40 pressure roll B is also adjustable to accommodate bats of various sizes; one of the supporting arms 47 being provided with a slot 50 which receives a bolt 51 carried by one end of a lever 52, which lever is journaled on a rock shaft 48 and its other end connected to a yoke member 53. This yoke member is controlled for automatically raising and lowering roll B in timed relation to the starting and stopping of the machine. To accomplish this, there is provided a cam shaft 54 on 45 which is mounted a cam 55 adapted to engage a roller 56 on the lower end of yoke member 53. On the outer end of cam shaft 54 there is carried a plate 57 having a stop 58 adapted to engage one end of a clutch operating arm 59. This 50 clutch operating arm 59 is pivoted at 60 and is provided with a yoke 61 which engages a clutch sleeve 62 keyed to the transverse shaft 12. The outer end of the yoke arm 59 is provided with a suitable control handle 63. The cam shaft is rotated from shaft 12 through a belt 64 and suitable speed reducing means 65. The operation of the machine is as follows: The bats are rolled in the usual manner in a piece of burlap or flannel—that is, four to eight bats are laid one upon the other on the flannel and rolled up from tip to brim. The rolled assembly is placed in the trough formed by the rolls A, C, and D, and, if necessary, rolls C and D may then be adjusted by turning of hand wheel 30 to properly space them for the size of the bat being manipulated. Roll B may likewise be properly adjusted by properly setting the bolt 51 in the slot 50 and then securing same in place. The clutch is now thrown in by the operating lever 63, whereupon shaft 12 will be rotated and the gear train driven

5 to simultaneously rotate rolls A, C, and D. The cam 55 will simultaneously move out of engagement with roll 56, whereupon roll B will be lowered into position on the top of the roll of bats E and frictionally driven by engagement therewith. After a predetermined time, cam 55 will engage roll 56 to lift roll B out of engagement with hat bats E and the stop 58 on member 57 will engage the inner end of clutch shaft 59 to throw the clutch out of engagement. The bats are then 10 formed for another "round".

15 During the operation of the machine, due to the pressure of roll B acting downwardly on the top of the roll E, it will be seen (Fig. 5) that the bat will be circumferentially corrugated by the top and bottom rolls A and B as part of the bat will be forced downwardly into the grooves of the roll A and upwardly into the grooves of the roll B. Simultaneously, the rolls C and D will produce longitudinal corrugations or flutes in the 20 hat bat. As the bat E is rotated, the corrugations from the top and bottom rolls will be broken up by the flutes of the side rolls, and vice versa. In this way, the hat bats are subjected to a double action—that is, they are simultaneously manipulated both circumferentially and transversely. As there is a tendency on each "round" 25 to reduce the size of the bat due to the manipulation which causes the felt or fur to interlock and harden, it is possible to finally adjust the 30 side rolls after each "round" to take up for such reduction in the size of the bat. It will be seen that the action is extremely smooth, elastic, and gentle, and avoids defective work. As the bat is simultaneously acted upon by the four rolls, it is 35 subjected to considerable more manipulation than is accomplished when fewer than four rolls are utilized, and, as a result, the speed of manipulation is considerably increased. Moreover, as the bats are arranged in a substantially rectangular trough, it is impossible for them to work 40 out of same.

45 As many changes could be made in the above construction and many apparently widely different embodiments of this invention could be made without departing from the scope thereof, it is intended that all matter contained in the above description or shown in the accompanying drawings shall be interpreted as illustrative and not 50 in a limiting sense.

55 It is also to be understood that the language used in the following claims is intended to cover all of the generic and specific features of the invention herein described and all statements of the scope of the invention which, as a matter of language, might be said to fall therebetween.

50 I claim as my invention:

1. In a machine of the character described, a bottom roll, a pair of side rolls arranged in a plane above said bottom roll and spaced apart to cooperate therewith to position a roll of bats, and a top roll above said other rolls adapted to exert pressure on the bats, said top and bottom rolls being circumferentially corrugated and said side rolls being transversely corrugated.

60 2. In a machine of the character described, a bottom roll, a pair of side rolls arranged in a plane above said bottom roll and spaced apart to cooperate therewith to support a roll of bats between them, said bottom roll being circumferentially grooved and the side rolls comprising a pair of oppositely disposed heads and transversely extending rods supported by said heads, and a pressure roll arranged above said other rolls and

circumferentially grooved similarly to said supporting roll.

3. In a machine of the character described, a transversely extending shaft, a bottom roll mounted thereon, a pair of upwardly extending radial arms pivotally mounted on said shaft, the upper end of said arms extending beyond the periphery of the supporting roll, a shaft supported

between the ends of said arms, a roll supported on said shaft, a gear supported on the end of said shaft, a second gear supported on the end of said longitudinal shaft, and an intermediate gear carried on said radial arm interconnecting said gears. 5

HOMER A. GENEST.
